UNITED STATES PATENT OFFICE.

JOSEPH SCHULTZ, OF CLEVELAND, OHIO.

SLIDING-DOOR STRUCTURE.

Application filed March 2, 1925. Serial No. 12,527.

To all whom it may concern:

Be it known that I, JOSEPH SCHULTZ, a citizen of the United States, resident of the city of Cleveland, county of Cuyahoga, and

State of Ohio, have invented new and useful Improvement in Sliding-Door Structures, of which the following is a specification, the principle of the invention being herein explained and the best mode in which 10 I have contemplated applying that principle, so as to distinguish it from other invention.

My invention relates to sliding-doors for closing the door-ways of elevator-shafts, its 15 object being to provide such closure by means of a door or doors suspended in such door-way and at the same time provide means for supporting the lower ends of the doors against swinging in a direction transverse with respect to the sliding movement 20 thereof, without the use of grooves formed in the door-sills which have heretofore been used in connection with pins fixed to the lower door end or ends and engaging said 25 grooves for that purpose, which grooves occasion frequent annoyance and trouble by becoming clogged with refuse, sweepings, etc., as is well known to those skilled in the art.

30 The said invention consists of means hereinafter fully described and particularly pointed out in the claims.

The annexed drawings and the following 35 description set forth in detail certain means embodying my invention, the disclosed means, however, constituting but one of the various mechanical forms in which the principle of the invention may be employed.

In said annexed drawings: 40 Figure 1 represents a front elevation of an elevator-shaft door-way provided with doors constructed in accordance with my invention.

Fig. 2 represents a section taken upon the 45 plane indicated by line II—II in Fig. 1, showing the door-way closed, and also a fragmentary section of the elevator.

Fig. 3 represents a section similar to that of Fig. 2, showing the door-way open.

50 Fig. 4 represents a section similar to that of Figs. 2 and 3, but showing a modified form of my invention.

Fig. 5 represents a rear elevation of a fragmentary part of such door-way and

55 doors of the form shown in Fig. 1.

Fig. 6 represents, upon an enlarged scale,

a fragmentary part of the structure, and taken upon the plane indicated by line VI—VI, in Figs. 1 and 2, also showing a fragmentary part of the elevator.

60

In the illustrated embodiment of my invention, the door-way is formed by the frame consisting of the bottom or sill-plate 1, the side-members 2 and 3 respectively, and the top member 4. In the form shown in 65 Figs. 1, 2, 3 and 5, the closure for the door-way consists of three parts, a part 5 fixed in any suitable manner and closing one end of the door-way (the right-hand in this particular described structure), a sliding-door 70 6 and a sliding-door 7. Doors 6 and 7 are suspended from the top member 4 in the usual manner, as by suitable rollers running on suitable tracks (not shown) and as it well known. All three of these described closure 75 members are off-set from each other in a direction transverse with respect to the direction of sliding, as shown, so that they may pass each other, as is also customary and well known in this type of door.

80

Beneath the sill-plate 1 and communicating with the elevator shaft 8 is a horizontal recess 9 formed in the front wall 10 of the said shaft, Figs. 5 and 6. Fixed in any suitable manner, as by screws 11—11, to the 85 bottom of said sill and projecting downwardly into the said recess 9, which may conveniently be of T form as shown. This bar runs parallel with the recess.

85

The right-hand end of door 6 is provided 90 with a bracket 13, fixedly secured to its bottom portion. This bracket extends horizontally forward to, then into said shaft, and back into the recess 9, Fig. 6. The lower extremity of the bracket is provided 95 with a vertical plate 14 secured to the main portion 15 of the bracket by means of a bolt 16 and spaced therefrom by a separator 17. Vertical wear plates 18—18 are suitably secured to the insides respectively of parts 14 and 15 by suitable means, such as screws 19, and form a groove 20 into which the bar 12 (in this case the web of the T-bar) extends, Fig. 6. The width of the groove is made sufficient to allow for sliding 100 engagement of the bracket with the bar, and yet permit a minimum of relative movement thereof in a direction transverse with respect to the direction of sliding, as will be understood.

105

It will therefore be noted that the lower end of the door 6 is supported so as to be 110

prevented from swinging in such described transverse direction.

Similarly, the left-hand of door 7 is provided with a bracket 13' whose lower end is 5 of the same construction above described, and similarly engages the bar 12.

Door 6, however, is located further out from the shaft, than is door 7, and hence the horizontal part 21 of its bracket is somewhat 10 longer than the corresponding part 21' of bracket 13', as shown in Figs. 1 and 6.

In order to permit door 7 to pass door 6, when they are in their opening position, that portion of part 21 of bracket 13, which is in 15 alinement with door 6, is depressed below the lower end of said door 7, to form a groove 22, Fig. 6, whereby such passing and their overlapping is permitted, as shown in Fig. 3.

20 In the structure illustrated by Fig. 3, I have shown my invention as applied to a closure consisting of but two doors alined with each other and of course sliding in opposite directions when actuated to open.

25 In this form, the bottom of each door, as before, is provided with a bracket 23 similar to those above described, and since the doors are alined, these brackets may be made of a form identical with each other,

30 and also may, as shown, be made coextensive in length with their respective doors, as shown.

The lower ends of these brackets 23 are 35 of a cross-section similar to that of the brackets shown in Figs. 1 and 6, and similarly engage the bar 12, all as will be readily understood from the foregoing description of the first-described form.

40 The lower part of the recess 9 may be closed by means of a plate 24 suitably secured to the face of the walls 10, as shown in Fig. 6, leaving the upper portion open and communicating with the shaft.

45 As shown also, the main or body portion of each bracket is made from an upper section 25 and a lower section 26 united at the horizontal portion thereof by rivets 27. This feature makes it possible to always adjust the parts to fit a given door-way which 50 may by reason of defects of workmanship or erection vary in form or location from that which was intended or designed for it.

This is done by omitting the rivet hole 28 from the lower section 26 and before assembly. The upper section 25 is first secured to its door and then the latter is properly hung in the door-way. The lower section with its attached parts is then placed in its proper position engaging the bar 12 and moved immediately beneath the upper section 25 by hand. The proper place for the rivet hole in section 26 may be marked through the rivet hole 29 in section 25. The lower section is then removed and the required rivet hole drilled. Said section is

then again placed in position engaging bar 12, the two sections 25 and 26 brought together and then riveted, thus imparting the proper position to the bracket.

What I claim is:

1. In a sliding-door structure, the combination of an elevator-shaft door-way; a sliding-door suspended in such door-way and provided with a member extending into the elevator shaft; and means mounted below the plane of the door sill engaging said member and adapted to prevent movement thereof in a direction transverse with respect to the direction of sliding of said door.

70 2. In a sliding-door structure, the combination of an elevator-shaft door-way; a sliding-door suspended in the latter and provided at its bottom with a fixed bracket extending toward and then down into the elevator shaft; and means fixed to the adjacent shaft wall for slidably engaging the lower end portion of such bracket.

75 3. In a sliding-door structure, the combination of an elevator-shaft door-way; a sliding-door suspended in such door-way, one shaft-wall being provided with a recess communicating with the shaft beneath the lower plane of said door-way; a member secured to the said door and extending into said shaft and recess; and means in the latter for engaging said member and adapted to prevent movement of the latter in a direction transverse with respect to the direction of sliding of said door.

80 4. In a sliding-door structure, the combination of an elevator-shaft door-way; a sliding-door suspended in said door-way; the shaft-wall beneath the latter being provided with a recess communicating with the elevator shaft; a bracket secured to the lower part of said door, extending into the shaft and into said recess; and a bar secured in said recess and parallel with the direction of door-movement; said bracket slidably engaging said bar.

85 5. In a sliding-door structure, the combination of an elevator-shaft door-way; a sliding-door suspended in said door-way; one shaft-wall being provided with a horizontal recess communicating with the shaft and located beneath the door-sill; a bracket secured to the lower part of said door, extending into the shaft and into said recess; and a horizontal bar fixed in the latter; said bracket slidably engaging said bar.

90 6. In a sliding-door structure, the combination of an elevator-shaft door-way; two sliding-doors suspended in the latter and offset from each other in a direction transverse with respect to the direction of their sliding movement; each of said doors being provided at the bottom with a bracket extending into said shaft; fixed means for slidably engaging the lower ends of said brackets; the outermost of said doors being formed

with a depressed portion in alignment with and below the lower end of the other door, whereby the latter may pass such outermost door.

5. 7. The combination with a sliding door; of a bracket secured thereto and consisting of a main member and means forming the end portion of said main member adapted to slidably engage a suitable guide; said

main member consisting of a section directly 10 secured to the door, extending outwardly therefrom, and a separate section secured thereto and having its outer portion extending transversely of said first-named section.

Signed by me this thirteenth day of Feb- 15
ruary, 1925.

JOSEPH SCHULTZ.
